UNITED STATES PATENT OFFICE.

HERMAN F. BUSCH, OF MILLVALE, PENNSYLVANIA, ASSIGNOR TO ARMSTRONG CORK COMPANY, OF PITTSBURGH, PENNSYLVANIA, A CORPORATION OF PENNSYLVANIA.

MACHINE FOR CUTTING SHEETS OF CORK PAPER.

1,122,070.

Specification of Letters Patent. Patented Dec. 22, 1914.

Application filed April 24, 1914. Serial No. 834,131.

To all whom it may concern:

Be it known that I, HERMAN F. BUSCH, a citizen of the United States, residing at Millvale, in the county of Allegheny and State of Pennsylvania, have invented a new and useful Improvement in Machines for Cutting Sheets of Cork Paper, of which the following is a full, clear, and exact description, reference being had to the accompanying drawings forming part of this specification, in which—

Figure 1 is a plan view of a machine embodying my invention; Fig. 2 is an end elevation looking toward the upper end of Fig. 1; Figs. 3 and 4 are sections taken, respectively, on the line III—III and IV—IV of Fig. 1; Fig. 5 is a plan view of the rotary carrier or magazine for the cork blocks; and Fig. 6 is a detail perspective view of one of the cork holders.

My invention has relation to machines for cutting sheets of cork paper from cork blocks, and is designed to provide a machine of this character which is simple and reliable in its operation, and by means of which the work can be very rapidly done. Also to provide a machine of this character by which sheets of any desired thinness, up to about four hundred sheets per inch, can be accurately cut.

The nature of my invention will be best understood by reference to the accompanying drawings, in which I have shown one embodiment thereof and which will now be described, it being premised, however, that various changes may be made in the machine, without departing from the spirit and scope of my invention, as defined in the appended claims.

40 In the drawings, the numeral 2 designates the supporting frame of the machine, which is formed at its top portion with suitable guides 3, to receive a longitudinally movable table or slide 4. 5 is a second slide or table which is mounted on suitable guides 6, of the slide or table 4, to move thereon transversely or in a direction substantially at right angles to the direction of movement of the slide 4.

45 7 designates a suitable shaft or arbor driven in any suitable manner, as by a pulley 8, and having at its overhanging end the disk cutter 9, which rotates in a vertical plane.

50 The numeral 10 designates a rotary carrier

or magazine to the periphery of which are secured the cork blocks to be cut into sheets. This carrier is of generally circular form, and is rigidly secured to a vertical driving shaft 11. The peripheral portion of the carrier is formed with a plurality of vertically extending V-shaped guideways 12, each adapted to receive a segmental cork holder 13. Each cork holder is formed with the dovetailed projecting portions 14 on the inner face thereof, to slidably engage the ways or guides 12. Each carrier is also preferably provided with a suitable handle 15 at its upper end to facilitate its insertion into and removal from the carrier. The outer convex face of each holder consists of a segment of a cylindrical surface, whose radius is struck from the center of the shaft 11. The cork blocks A which are to be cut are suitably secured to these holders, preferably by coating them with a suitable hot cement and pressing them firmly on to the convex surface of the holder. When the cement has cooled, the holders are placed in the carrier as required. It will be seen that the cork blanks in being applied to the holders are bent to conform to the curvature of the convex outer sides thereof and when placed in the carrier are so positioned that the cutting edge of the disk cutter 9 is tangential to the outer surface of the blocks. Secured to the shaft 11 below the carrier and also secured to the carrier is a large gear wheel 16, having an annular double beveled bearing portion 17 on its lower face which is adapted to rotate in the correspondingly shaped raceway or bearing 18 on the upper face of the table 5. In order to relieve this bearing somewhat, the lower end of the shaft 11 may be stepped upon an adjustable bearing screw 19, seated in the table 5. This screw by proper adjustment can be made to take any desired part of the load, and thus relieve the bearing on the annular raceway 18.

55 The feeding movement of the carrier is effected by a continuous feeding movement imparted to the table 5. This may be effected in any suitable manner, as may also the driving of the carrier. In the drawing, I have shown the gearing now to be described.

The large gear wheel 16, which is attached to the carrier, is driven by a pinion 20, journaled on the table 5 and which is driven by

a pinion 21, on the vertical shaft 22. The shaft 22 carries a bevel gear wheel 23, which is driven by a pinion 24, on the transverse shaft 25, carrying the loose pulley 26 and the fast pulley 27.

28 is a belt shifter for shifting a driving belt from one of these pulleys to the other, to thereby control the operation of the rotary carrier. This belt shifter may be operated by connections, such as indicated at 29 and 29^a, extending to the operator's station.

30 is a bevel gear wheel on the upper end of the shaft 11, which drives a corresponding gear wheel 31 on the longitudinal shaft 15 32. This shaft carries a pinion 33 which, through the train of reducing gears 34, 35, 36, 37, 38 and 39, drives a longitudinal shaft 40, at one side of the table 5 and supported in suitable bearings 41, carried thereby. The shaft 40 may have any desired number of bevel gears 42 (two being shown) each of which drives a bevel gear 43 on transverse shafts 44. The shafts 44 engage nuts on the under side of the table 5.

25. By the driving connections last described, the rotary movement of the carrier or magazine actuates the shaft 40, and thereby through the shafts 44, imparts a continuous feeding movement of the table 5 and of the 30 carrier toward the cutter 9, to make successive cuts. In this feeding movement, it will be seen that all the gearing moves with the table 5, being mounted thereon. The train of reducing gearing above described may contain one or more interchangeable members, whereby the rate of feed can be varied to vary the thickness of the paper sheets as may be desired.

In order to enable the table to be quickly 40 run up to the cutter or backed away from it, the gear 39 is connected with the shaft 40 through a suitable clutch 46. This clutch is controlled by the shifting rod 46^a, which also preferably extends to a point near the 45 operator's station. When this rod is actuated to throw out the clutch 46, the shaft 40 can be actuated by the hand wheel 47, or any other suitable means, to thereby quickly move the table 5 toward and away from the 50 cutter.

The longitudinal movement of the table 4 is for the purpose of adjusting the table 5, carried thereon, to compensate for wear of the cutter. These cutters wear quite 55 rapidly, and in operation become greatly reduced in diameter before being discarded. This adjustment of the table 4 can be effected by means of the screw shaft 48, which is shown as having an operating hand-wheel 60 49. Suitable means, such as the binding screws 50 may be provided for rigidly clamping the cork holders to their seats in the carrier, thereby preventing any looseness or play therein.

65 The advantages of my invention result

from the provision of a machine having a rotary magazine or cork carrier to and from which the cork blocks can be readily secured and removed and which holds the said blocks in curved form, so that the cutter 70 can operate thereon in a tangential plane, said carrier being capable of a continuous feeding movement toward the cutter. In this manner, a very considerable number of cork blocks can be simultaneously mounted 75 on one carrier capable of a relatively high speed of rotation. This enables the machine to have a large total output, as well as extreme accuracy in operation. The 80 actual use of a considerable number of these machines has demonstrated that each machine is capable of cutting from fifteen thousand to twenty thousand cork sheets, per day, and that the sheets produced are of uniform and perfect character and can 85 be actually cut to a much greater degree of thinness than has heretofore been possible with accurate work.

It will be readily understood that the machine is capable of wide variations in the 90 details. Thus, any suitable gearing may be provided for driving the rotary carrier, as well as for operating the feeding movement of the carrier, and various other changes 95 may be made.

I claim:

1. A machine of the character described, comprising a rotary support for the cork blocks, means for holding the cork blocks thereon in curved position, a cutter arranged 100 tangentially to the outer surfaces of the blocks on the carrier, and means for imparting a continuous feeding movement to the carrier, substantially as described.

2. A machine of the character described, comprising a carrier movable about a fixed center, means for holding a cork block on said carrier in curved form, a cutter disk tangential to the outer surface of the cork block on the carrier, and means for imparting a feeding movement to the carrier, substantially as described.

3. A machine of the character described, comprising a rotary carrier having a plurality of peripheral seats, cork holders adapted to be removably secured in said seats and having curved outer surfaces to which the cork blocks to be cut are secured, a tangentially arranged cutting disk, and means for imparting a feeding movement to 120 the carrier, substantially as described.

4. A machine of the character described, comprising a transversely movable support, a longitudinally movable sub-support, a rotary carrier mounted on the transversely 125 movable support and having means for securing thereto in curved form a plurality of cork blocks, means for imparting a continuous feeding movement to the first named support and carrier, and means for adjust- 130

ing the sub-support, substantially as described.

5. A machine of the character described, comprising a rotary carrier having means for securing to the periphery thereof a plurality of cork blocks in curved form, a support upon which the table is mounted, means for imparting a continuous feeding movement to the support and carrier, means 10 for throwing the feeding gear out of action, and other means for actuating the support when the feeding gear is thrown out of action, substantially as described.

6. A machine of the character described,

comprising a carrier movable about a fixed center, means for holding a cork block on said carrier in curved form, a cutter disk tangential to the outer surface of the cork block on the carrier, and means for imparting a relative feeding movement between the 20 carrier and the cutter, substantially as described.

In testimony whereof, I have hereunto set my hand.

HERMAN F. BUSCH.
